UNITED STATES PATENT OFFICE.

WILHELM JULIUS TEUFEL, OF STUTTGART, GERMANY.

PLASTER BANDAGE.

1,003,161.

Specification of Letters Patent. Patented Sept. 12, 1911.

Application filed May 13, 1910. Serial No. 561,205. (Specimens.)

To all whom it may concern:

Be it known that I, WILHELM JULIUS TEUFEL, a subject of the Emperor of Germany, residing at Stuttgart, Germany, have 5 invented certain new and useful Improvements in Plaster Bandages or Materials, of which the following is a specification.

Plaster bandages or materials in which the fabric containing the plaster substance 10 is self-elastic or of a crape-like or openwork nature are well-known.

The present invention relates to an improvement in plaster materials with a self-elastic or expansible or stretchable body and 15 consists in a fabric foundation in which a crape-like or open-work fabric or surface is used in combination with a plain or smooth fabric or surface.

The invention may, for example, be carried out as shown in the drawing which represents a bandage consisting of longitudinal strips of a plain smooth fabric *a* which alternate with strips *b* of a crape-like or crinkled material. Such a bandage has over 20 the usual bandages of which the material consists solely of crape-like fabric, the advantage that the bandage adheres firmly at

the smooth parts, whereas at the open portions, that is to say, the open spaces provided by the crape-like fabric, it admits the 30 entrance of air, while the transverse passages or openings provided for by the crape-like material form passages through which any discharge issuing from, say a wound, can pass away or be collected.

It will be obvious that the two kinds of material or surface can be relatively arranged in a variety of ways, other than in parallel alternate strips of plain and crape-like material and the present invention is 40 not restricted to the latter arrangement.

What I claim and desire to secure by Letters Patent is:—

An adhesive plaster consisting of a porous fabric formed of alternating smooth and 45 crinkled portions and a coating of adhesive composition covering substantially the entire face of said fabric.

In testimony whereof I affix my signature in the presence of two witnesses.

WILHELM JULIUS TEUFEL.
